CLAIM

The ornamental design for a bottle cap, as shown and
described.

DESCRIPTION

FIG. 1 is a front perspective view of a bottle cap in a first
position showing our new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof;

FIG. 8 is an enlarged front perspective view of the bottle cap
shown in FIG. 1 with the container removed;

FIG. 9 is a front perspective view of the bottle cap of FIG.
1 shown in a second position;

FIG. 10 is a front elevational view thereof;

FIG. 11 is a rear elevational view thereof;

FIG. 12 is a left-side elevational view thereof;

FIG. 13 is a right-side elevational view thereof;

FIG. 14 is a top plan view thereof;

FIG. 15 is a bottom plan view thereof; and,

FIG. 16 is an enlarged front perspective view of the bottle
cap shown in FIG. 9 with the container removed.

The broken lines illustrate structure or features that form no
part of the claimed design.
